UNITED STATES PATENT OFFICE.

JULIUS PEGEL, OF NEW YORK, N. Y., ASSIGNOR TO THE HARTFORD CARPET COMPANY, OF HARTFORD, CONNECTICUT.

DESIGN FOR A CARPET.

SPECIFICATION forming part of Design No. 12,865, dated April 11, 1882.

Application filed February 23, 1882. Term of patent 25 years.

To all whom it may concern:

Be it known that I, JULIUS PEGEL, of New York city, in the county and State of New York, have invented a new and original Design for Carpets, of which the following is a specification.

This invention relates to a new and original design for carpets and similar fabrics: and it consists in the novel grouping and configuration of figures hereinafter more fully described.

The accompanying photograph illustrates a face view of a carpet having my new design.

A is a blank field traversed irregularly by 15 small lichen or coral like figures, with blossoms *b*, and by stray leaf forms *c* between the large flower groups B, C, D, and E, and by the border-sprays of those groups. B, C, D, and E each rest on and partially conceal a 20 plain background, *a*, distinct from the blank field A, and consist of irregular groups of flower figures and leaves variously massed, as shown, and spreading out irregularly over the ground *a* and the adjacent parts of the 25 blank field A.

B is a group composed of the rose-and-leaf cluster F, (a full-blown rose in a mass of leaves, and above it a moss-rose bud,) surrounded by fern-leaves *d*, to the left a cluster 30 of five-leaved star-shaped flowers, *e*, below a cluster of circular star-shaped flowers and jutting-leaves, *h*, also a cluster above and to the right, *l*. B terminates on the right in a group of geranium leaves and blossoms, *f*, and 35 a rose and moss-rose bud in a leaf cluster, *g*.

C is a group composed of the rose-and-leaf cluster G, (two open roses in a leaf cluster, with two pendent moss-rose buds directly below,) surrounded by the flower-and-leaf clusters *k i m*, and the leaf clusters *n o i* have flag-like leaves.

D (shown in part on one side and in part on the other side of the photograph) consists of a group of geranium leaves and blossoms, 40 *p*, below them a group of small circular star-shaped flowers and leaves, *q*, on their right, and jutting out over *a*, a leaf group, *r*, and on their

left a moss-rose bud above, *s*, and below a cluster, *t*, of small star-shaped flowers and spreading open leaves.

E (shown in part on one side and in part on the other side of the photograph) consists of the rose-and-leaf cluster *u*, (an open rose, with leaves, and two moss-rose buds below it,) above it the spreading leaf cluster *v*, to the 55 right the group of small star-shaped flowers and leaves *w*, to the left the small star-shaped flower-and-leaf cluster *y*, and below that a similar cluster, *z*.

The effect of the whole design is as if the 60 background *a*, which remains compact and unbroken under the mass of the large flower groups B, C, D, and E, is torn and broken up in the spaces between such groups, and the blank field A, thereby disclosed, is filled with 65 the irregular fragments *b c*, heretofore described as lichen or coral like forms.

I claim—

1. The design for carpets, consisting of the group B, including the figures *F d e h l f g*, 70 substantially as shown.

2. The design for carpets, consisting of the group C, including the figures *G k i m n o*, substantially as shown.

3. The design for carpets, consisting of the 75 group D, including *p q r s t*, substantially as shown.

4. The design for carpets, consisting of the group E, including *u v w y z*, substantially as 80 shown.

5. The design for carpets, consisting of the figures *b c*, the group B, including the figures *F d e h l f g*, the group C, including the figures *G k i m n o*, the group D, including the figures *p q r s t*, the group E, including the 85 figures *u v w y z*, and the ground *a* and field A, substantially as shown.

6. The design for carpets, consisting of the figures *b c*, the ground *a*, and field A, substantially as shown.

JULIUS PEGEL.
